UNITED STATES PATENT OFFICE.

SIMON R. DEE, OF CHICAGO, ILLINOIS.

SCREW JACK.

Application filed September 30, 1921. Serial No. 504,407.

To all whom it may concern:

Be it known that I, SIMON R. DEE, a citizen of the United States, residing at Chicago, in the county of Cook and State of Illinois, have invented certain new and useful Improvements in Screw Jacks, of which the following is a specification.

This invention relates to a jack having a work transmitting rod which is reciprocated longitudinally through the medium of screw threads, and particularly to that type of screw jacks in which the range of movement of the work transmitting rod is multiplied by applying simultaneous longitudinal movement to the member in which the work transmitting rod is threaded, as, for instance, by constructing said member in the form of a sleeve which is itself threaded in the mounting for the jack and is positively 20 rotated in its mounting as well as upon the rod.

One object of the invention is to provide a simplified construction of screw jack of the class described, as well as an improved driving mechanism therefor, and to this end, one feature of the invention consists in providing for the threaded sleeve a driving wheel which surrounds the sleeve coaxially and has driving connection therewith without 25 restricting the longitudinal movement of the sleeve; the driving wheel being confined axially in the mounting of the sleeve and being itself driven through suitable speed reduction gearing so that as the driving 30 wheel is rotated, the sleeve will be fed longitudinally by its threaded connection with its mounting and carry the working rod with it, and at the same time will feed the working rod relatively to the sleeve by reason of the 35 threaded connection of the rod and sleeve and the projection of a pin transversely from the working rod and into a groove of the mounting for retention of the rod against 40 rotation.

Another object is to render the jack self arresting upon the attainment of its limit of movement in either direction; and to this end, a further feature consists in arranging a system of pull and thrust connections, 45 whereby one of the longitudinally reciprocating screw actuated members, or, if desired, either of said members, or both of them, can impart the throw to the reversing clutch; a subordinate feature incident to this part of the preferred embodiment of the invention consisting in locating a clutch rod

coaxially with the working rod and in a bore formed in the latter so as to receive therefrom, alternately, a thrust and a pull as the working rod reaches the limits of its movement, and arranging suitable lever connections between this clutch rod and the clutch; and still another subordinate feature incident to this part of the preferred embodiment of the invention consists in utilizing for the clutch body the same transmitting connections as are employed for controlling the clutch by hand.

The screw jack herein described is adapted for performing work upon a truck or vehicle upon which it may be mounted, as, for instance, the work of moving the vehicle a limited distance from an obstacle which it may encounter, such as a road depression or obstruction that cannot be overcome by the normal propelling power of the vehicle; and, to this end, a flexible connector is applied to the end of the working screw and suitably guided in a direction that adapts it to be passed beyond the confines of the vehicle and attached to a fixed object or anchorage, against which the jack can pull in moving the vehicle.

In the accompanying drawings—

Figure 1 is a longitudinal axial section of a screw jack embodying the features of the present invention which are, immediately concerned with the construction of the jack.

Figure 2 is a transverse section on the line 2^x—2^x of Figure 1.

Figure 2^a is a section on the line 2^{ax}—2^{ax} of Figure 1.

Figure 3 is a side elevation of a motor vehicle illustrating one use to which the jack may be put.

Figure 4 is a view similar to Figure 3 showing another use to which the jack may be put; and

Figure 5 is a side elevation showing the jack embodied in a form adapted to serve the purposes of an ordinary portable lifting jack.

Referring to Figures 1, 2, and 2^a, 6 represents the working rod adapted to perform work, as, for instance, by providing it with eye 7 to which may be attached a flexible cable or other connector. This rod is constructed with threads 8 and adapted to be driven in the direction of its longitudinal axis by relative rotation between the rod and a correspondingly threaded sleeve 9 surrounding it, which is similarly provided

with threads 10 working in the correspondingly threaded mounting 11. Longitudinal movement of the rod 6 is developed by rotating the sleeve 9, while the rod is held stationary by some suitable means, such, for instance, as a cross pin 12 traveling in the guideways 13, and by such rotation of the sleeve 9 not only is the rod 6 fed longitudinally and relatively to the sleeve, but the sleeve also moves longitudinally in the mounting 11 and correspondingly amplifies the movement of the rod by carrying the rod with it at the same time that it is thrusting the rod ahead of it.

15 In order to rotate the sleeve 9 and still leave it free to move longitudinally, a drive wheel 14 is fitted coaxially upon the sleeve and enters into driving connection with the latter through means of a key 15 working in the longitudinal key-way 16 of the sleeve, the wheel being confined against axial movement during such rotation, by its confining housing 11^a formed with the mounting 11. Wheel 14 is driven by small pinion 17 on a shaft 18 that is in turn driven by a clutch member 19 which is adapted to interengage with either of two clutch members 20, 21, which are constantly driven by the bevel pinion 22 on a power shaft 23. Clutch member 19 is controlled by fork 24 mounted on rock shaft 24^a and embracing the clutch member 19, and a crank arm 25 on the outer end of said rock shaft, connected through link 26 to the crank lever 27 which is fulcrumed at 28 and adapted to be manually controlled by a handle 29.

With the construction thus far described, and assuming that rotation is being imparted to the shaft 23, it is simply necessary 40 to move the handle 29 to throw the clutch 19 into mesh with one or the other of the oppositely rotated clutch members 20 and 21, when a longitudinal movement will be imparted to the working rod 6 which is equivalent to the combined feeding movements of the screws 8 and 10. If the handle 29 be moved in one direction, the rod 6 will be fed outward, and if the handle be moved in the other direction the rod will be fed in- 50 ward.

In order to prevent the feed of the rod 6 from over-running its limit, particularly when the shaft 23 is running continuously, the lever 27 is provided with an automatic clutch rod 30 that is provided with one or more shoulders through which it is adapted 55 to encounter a longitudinally reciprocating member, for instance, the shoulder provided in the collar 31 which is in the path of the end 32 of the sleeve 9, the shoulder 33 on rod 30 which is on one side of the head 34 in the bore 35 of the rod 6, or the shoulder 37 which is on the inner end of the clutch rod 30 adapted to be encountered by the 60 inner face of said head 34. Clutch rod 30

is preferably provided with a displaceable locking dog 38 adapted to drop into either of the seats 39 and hold the rod at its respective limits of movement.

The mounting 11 is preferably divided in 70 the medial plane of the housing 11^a to facilitate assembly around rod 6, sleeve 9, and drive wheel 14, and has its members united by tie bolts 40 or equivalent means. For introduction of the pin 12 into screw 6, the 75 removable plug 41 is provided, and for assembly of the shaft 18, clutch members 19, 20, 21, and driving gear 22, the housing 11^b may be provided with a separable cap 11^c removably secured in position by screws 11^d. 80

A screw jack of the character described is adapted for various uses, some of which are herein suggested. For instance, the jack may occupy the position shown at 11 in Figure 3, where the eye 7 of rod 6 is connected by flexible connector 42 with the arm 43 of a crank lever 44 that is adapted to raise the dumping body 45 upon its rear pintle 46. Or, as shown in Figure 4, the jack occupying the position 11 may be connected with a flexible cable 42^a guided around sheaves 47, 48, 49, to a point beyond the rear confines of the vehicle, or past the pulleys 48^a-49^a to a point beyond the forward confines of the vehicle, and there provided with a hook 50 or other anchoring or engaging means, so that the jack may be utilized to pull the vehicle beyond an obstruction, or to slide a heavy package up an inclined tailboard into the body 45. 95

The lifting lever 43, 44 may be present in the arrangement of Figure 4 just as in Figure 3, means being provided for holding the cable 42 out of the way of the cable 42^a while the latter is being used, as, for instance, by detaching the hook 42^b of the working rod 6 before inserting the hook 42^c, and then hanging the cable 42 in the sling 42^d and engaging its hook over the pin 42^e. 105

As shown in Figure 5, the casing 11, 11^a, 11^c may be provided with a supporting base 11^d and an engaging head 7^a for an axle or other element to be lifted, and thereby adapted to serve as a portable lifting jack. 110

Shaft 23 will be driven by power connection, such, for instance, as that provided by bevel gear connection 51, 52 with the power shaft 53 of a motor vehicle as suggested in Figure 3, or by a sprocket chain 54 which will receive an ordinary pull chain, as suggested in Figure 5. 115

I claim:

1. In a screw jack, a longitudinally reciprocating screw, a drive wheel therefor, a shaft actuating said drive wheel, a reversing 125 clutch for driving said shaft, actuating connections for said clutch, and means for controlling said actuating connections comprising a longitudinally movable member extending substantially parallel to the screw 130

and having a part lying in the path of and encountered by the latter, as it nears the limit of its movement.

2. In a screw jack, a longitudinally reciprocating screw, a drive wheel therefor, a shaft actuating said drive wheel, a reversing clutch for driving said shaft, actuating connections for said clutch, and means for controlling said actuating connections comprising a longitudinally movable member extending coaxially into the screw and having shoulders within and without the screw, that are engaged by the screw as it nears the limits of its movements.

3. In a screw jack, a reciprocating work-transmitting screw, a pin projecting transversely from said screw, a housing surrounding said work-transmitting screw and having a groove paralleling the same, in which the end of said pin travels during the reciprocation of the screw, a tubular screw internally threaded to said work-transmitting screw and having external threads through which it is both fed and supported in the housing, and means for rotating the tubular screw relatively to both the housing and the work-transmitting screw.

4. In a screw jack, a housing constructed with an internal feeding thread, a tubular screw having external threads fitted to said feeding thread, a driving wheel confined against axial movement in said housing, surrounding said tubular screw and adapted to rotate the same without restricting its longitudinal movement, a work-transmitting screw threaded to the interior of said tubular screw, an extension on the housing beyond the threads of the housing which receive the tubular screw, said extension surrounding a portion of the work-transmitting screw between its outer end and the threads through which it engages the tubular screw and guiding said outer end in its reciprocation and having internal grooves on diametrically opposite sides of and paralleling said work transmitting screw, and a pin extending transversely through said work-transmitting screw and entering said grooves to hold the work-transmitting screw against rotation.

Signed at Chicago, Illinois, this 20th day of September, 1921.

SIMON R. DEE.
